US00D966556S

(12) **United States Design Patent** (10) **Patent No.:** **US D966,556 S**
(45) **Date of Patent:** **** Oct. 11, 2022**

(54) **LADDER**

(71) Applicant: **MURPHY LADDER LLC**, West Haven, UT (US)

(72) Inventor: **Jeremy Barker**, Morgan, UT (US)

(73) Assignee: **MURPHY LADDER LLC**

(**) Term: **15 Years**

(21) Appl. No.: **29/716,974**

(22) Filed: **Dec. 13, 2019**

(51) LOC (13) Cl. **25-04**

(52) U.S. Cl. **D25/64**

(58) **Field of Classification Search**

USPC **D25/62-65, 68, 69**

CPC **E06C 1/39; E06C 1/32**

See application file for complete search history.

(57) **CLAIM**

The ornamental design for a ladder, as shown and described.

DESCRIPTION

FIG. 1 is a front perspective view of a ladder according to a first embodiment of my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is bottom view thereof;

FIG. 9 is a front perspective view of a ladder according to a second embodiment of my new design;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is bottom view thereof;

FIG. 17 is a front perspective view of a ladder according to a third embodiment of my new design;

FIG. 18 is a rear perspective view thereof;

FIG. 19 is a front view thereof;

FIG. 20 is a rear view thereof;

FIG. 21 is a right side view thereof;

FIG. 22 is a left side view thereof;

FIG. 23 is a top view thereof; and,

FIG. 24 is bottom view thereof.

The broken lines illustrate portions of the ladder that form no part of the claimed design.

1 Claim, 24 Drawing Sheets
